UNITED STATES PATENT OFFICE

WILBUR S. LEWIS, OF LAKEWOOD, OHIO, ASSIGNOR TO THE NESTLE LE MUR COMPANY,
OF CLEVELAND, OHIO, A CORPORATION OF OHIO

HAIR CURLER

Application filed June 15, 1925. Serial No. 37,106.

My invention relates to curlers upon which strands of hair are coiled and stretched during the heating operation of permanent waving processes.

In forming permanent waves in human hair, it is customary to divide the hair into strands which are coiled around curlers of desired design and secured, and then stretched lengthwise while secured in coiled relation. Such curlers are generally formed of co-axially extending relatively rotatable sections so that the strand can be secured to each section and stretched by the relative rotation of the sections.

In order to prevent the tension of the stretched hair of unwinding such types of curlers, clutch or equivalent mechanism is provided intermediate the sections. In some cases the sections are not movable lengthwise and the clutch mechanism permits relative rotation of the sections in one direction only, while in other cases the sections can be rotated in either direction while the sections are moved longitudinally relatively. It is objectionable to adjust the sections lengthwise in order to rotate them relatively to stretch the strands of hair because of the additional operation which requires time. Sections which can be rotated in one direction only are objectionable because operators become proficient in coiling the strands in either one direction or the other, and with this class of curlers the operator is required to coil the strands in one direction.

An object of my invention is to provide a tension device for a curler composed of co-axially extending sections which will permit relative rotation of the sections in either direction without longitudinal adjustment, and which will prevent the tension of the stretched hair from rotating the sections relatively.

A further object of my invention resides in the provision of a simple, inexpensive curler which is comprised of relatively rotatable sections which can be readily assembled together to prevent relative longitudinal movement.

These and other objects and the invention

itself will appear in the following detailed specification.

In the accompanying drawings, Figure 1 is a side elevation of a curler embodying my invention; Figure 2 is a longitudinal sectional view of the same; Figure 3 is a side elevation of the rod section prior to assembly with the tube section; Figure 4 is a transverse sectional view of the assembled curler taken on line 4-4 of Fig. 2; and Figure 5 is a transverse sectional view of the assembled curler taken on line 5-5 of Fig. 2.

Referring now to the drawings by characters of reference, 10 represents one section of a curler which is a tube open at each end and preferably formed of round metal. The other section 11 of the curler is preferably formed of metal and is in the form of a rod which is of slightly less diameter than the interior wall of the tubular section.

The rod section extends co-axially through the tube section, and is flattened at one end to provide a finger grip 12, which the operator can grasp to rotate the rod. The other end 13 of the rod projecting from the tube is also flattened and is provided with a slot 14 in which a string, extending around a strand of hair can be secured. The flattened ends of the rod are formed of sufficient width to also serve the purpose of engaging the ends of the tube, to secure the tube so that it will not move lengthwise upon the rod.

A central portion of the rod 15 is reduced in diameter and provided with a longitudinally extending slot 16 in which the clutch or tensioning mechanism is anchored. The tension mechanism consists of two leaf springs 17 and 18, which have one end inserted in the slot 16 in the rod. The springs extend around the rod in opposite directions and bear against the inner wall of the tube 10, being under sufficient tension to frictionally prevent relative rotation of the rod and tube sections unless manual rotative pressure is applied. The rod can be rotated in either direction when the operator grasps the end 12 of the rod and exerts sufficient pressure to overcome the frictional tension exerted by the springs.

The rod section 11 is preferably formed of

- standard rod stock. Prior to assembly of the rod with the tube, the portion 15 is reduced and slotted and the flattened slotted end 13 is formed. The springs are then inserted in the 5 slot 16 and are bent around the rod whereupon the rod is inserted through the tube with the end 19 (Fig. 3) unformed. After such insertion the end 19 is flattened to provide the grip 12 and to retain the tube against longitudinal movement relative to the rod. It will 10 be understood that either one or both of the flattened ends 12 and 13 could be formed after the rod, with the springs assembled, is inserted through the tube.
- 15 In utilizing the curler for a waving process, a strand of hair is gathered from the scalp, after being treated with a softening solution, and is tied adjacent the scalp to the slotted end 13 of the rod by a string. The 20 free end of the strand is then coiled tightly around the tube, either over or under the same, in a direction toward the grip 12 and is tied to the tube at the end of the coil. By holding the tube the coiled hair will be 25 stretched by rotating the rod 11. The spring tension against the tube is sufficient to prevent rotation of the curler sections, so that the tension of the stretched hair will not rotate the curler sections relatively.
- 30 Variotis changes can be made in the structure described herein without departing from the spirit of my invention and the scope of what I claim.

What I claim is:—

- 35 1. A curler for carrying and stretching a strand of human hair comprising a tube upon which a strand of hair is coiled and secured, a rod extending through said tube having an enlarged end to which the strand of hair is 40 secured adjacent the scalp, a finger grip at the other end of said rod for rotating said rod relative to said tube to stretch the strand coiled on said tube, and laterally extending friction means disposed intermediate a side of 45 the rod and said tube and disposed intermediate the ends of the tube for preventing the tension of said strand of hair from rotating said tube and said rod relatively.
- 50 2. A curler rod, around which a strand of hair may be coiled in either direction and stretched, comprising two coaxially extending rotatable members secured together to prevent relative longitudinal movement, and a spring secured to one of said members at 55 an intermediate portion thereof and engaging the other of said members at a lateral surface thereof to put the members under lateral tension, the tension of said spring against said member being greater than the 60 tension of the stretched hair, one of the members projecting beyond both ends of the other member and comprising at one end a handle portion and at the other end a hair strand securing portion.
- 65 3. A curler around which a strand of hair

may be wound in either direction and stretched comprising a tube, a slotted rod extending through said tube and having enlarged ends to prevent relative longitudinal displacement of said tube therefrom, and a pair of oppositely extending springs having one end anchored in the slot in said rod and frictionally bearing under tension against an inner wall of said tube, said springs preventing relative rotation of said tube and rod until overcome by the manual rotation of said rod.

4. A curler for a strand of hair comprising a tube, a rod extending through said tube, said rod having its projecting ends flattened after insertion through said tube to secure said tube against longitudinal movement on said rod, one of said flattened ends providing a finger grip for rotating said rod relative to said tube, said rod comprising a portion disposed midway of its length, spring-pressed into frictional engagement against the inner walls of the tube.

Signed at Cleveland, in the county of Cuyahoga, State of Ohio, this first day of April, 1925.
